UNITED STATES PATENT OFFICE.

GUNNAR MADVIG, OF OAKLAND, CALIFORNIA.

DESIGN FOR A BRACKET FOR DRAPERY POLE OR ROD.

Application filed June 13, 1928. Serial No. 27,108. Term of patent 3½ years.

To all whom it may concern:

Be it known that I, GUNNAR MADVIG, subject of the King of Denmark, and a resident of the city of Oakland, county of Alameda, State of California, have invented a new, original, and ornamental Design for a Bracket for Drapery Pole or Rod, of which the following is a specification, reference being had to the accompanying drawing, forming part thereof.

Figure 1 is a side view of a bracket illustrating my new design.

Figure 2 is a perspective view of the bracket.

I claim:

The ornamental design for a bracket for drapery pole or rod substantially as shown.

GUNNAR MADVIG.
